UNITED STATES PATENT OFFICE.

CARLO GUATTARI, OF LONDON, ENGLAND, ASSIGNOR TO THE NEW MOTIVE POWER SYNDICATE, LIMITED, OF SAME PLACE.

GENERATION OF MOTIVE POWER.

SPECIFICATION forming part of Letters Patent No. 609,430, dated August 28, 1898.

Application filed April 24, 1897. Serial No. 633,692. (No model.)

To all whom it may concern:

Be it known that I, CARLO GUATTARI, engineer, a subject of the Queen of Great Britain, residing at 70 Milkwood road, Herne Hill, 5 London, England, have invented new and useful Improvements in the Generation of Motive Power, of which the following is a specification.

This invention has for its object to lessen 10 the consumption of fuel in the generation of motive power by the employment in the boiler of water impregnated with a compound of carbonic-acid gas whereby the generation of pressure is rendered possible with an ex- 15 penditure of heat energy very much below that by which it would be possible to generate steam in the ordinary way. The use of carbonic-acid gas alone for this purpose would not, however, be practicable, as the gas would 20 be quickly driven off from the water on the application of heat, with the result that the gas would become lost and the water be left in its natural condition.

The invention consists, essentially, in the 25 addition to the water of a compound resulting from the combination of carbonic-acid gas and a reagent, whereby the separate evolution of the carbonic-acid gas is prevented and thereupon condensing the combined gases 30 and vapors after they have been utilized. The reagent employed is preferably ethene 35 chlorid, commonly known by the name of "Dutch liquid," and the method of operating, which will be described with reference to the accompanying diagram, is as follows:

The carbonic-acid gas is generated in the ordinary way in a suitable closed receiver A, provided with an agitator, the receiver containing a carbonate in suspension in water, 40 to which hydrochloric or sulfuric acid is added from a receiver B, the receiver A being provided with a stoppered mouth, at which the ethene chlorid is introduced. The proportions which are found suitable are: water, 45 twenty-eight liters; whiting, seven kilograms; acid, two liters; ethene chlorid, one hundred and forty grams. But I do not limit myself in this respect. From the gas-generating vessel A the resulting compound gas passes off 50 through a pipe a (provided with a check-

valve) and is injected through a perforated pipe b into a saturator, being a closed receiver C, filled with water to be impregnated with, say, two or three times its own volume of the compound gas at the pressure at which 55 it was generated—that is to say, without being first compressed or liquefied. From the saturator C the solution or water now charged with the compound gas is drawn by the feed-pump D and supplied to any ordinary boiler 60 E, fired in the usual manner. From the boiler the combined steam and gases therein evolved are supplied to an engine K, and after doing work therein are exhausted into a surface condenser F, of any suitable construction, 65 cooled by water in the ordinary way, wherein condensation takes place without separation of gas, and from which the condensed solution or water still charged with gas is extracted by an air-pump G and delivered to a 70 receiver H, (which may be open to the atmosphere,) from whence it is drawn by any suitable steam-pump I and returned to the receiver C for use again.

The cycle above described may be repeated 75 over and over again continuously for any required number of hours, it being only necessary to repeat the operation of generating the compound of carbonic-acid gas and ethene chlorid in receiver A as often as may be necessary to make up for unavoidable loss.

Having now particularly described and ascertained the nature of the said invention and in what manner the same is to be performed, I declare that what I claim is—

The herein-described process of generating and applying motive power, the same consisting in generating gaseous pressure by evaporating a liquid charged with the compound formed by carbonic-acid gas and a reagent acting to prevent the evolution of the carbonic-acid gas, thereupon utilizing the said gaseous medium so generated and subsequently condensing the said gaseous medium to a liquid form which liquid may thereupon 95 be again evaporated and used as before.

CARLO GUATTARI.
